Primary Examiner — Leanne Was-Englehart*Assistant Examiner* — Yelizaveta Y Masalimova(74) *Attorney, Agent, or Firm* — TROUTMAN PEPPER
LOCKE LLP; Christopher C. Close, Jr.; Chris N. Davis(57) **CLAIM**

The ornamental design for a shoe as shown and described.

DESCRIPTION

FIG. 1 is a side elevation view of a shoe, showing my new design;
FIG. 2 is a rear elevation view thereof;

FIG. 3 is a front elevation view thereof;

FIG. 4 is a top plan elevation view thereof; and,

FIG. 5 is a bottom plan view thereof.

The longer-length broken lines represent stitching and form no part of the claimed design. The shorter-length broken lines showing certain portions of the shoe form no part of the claimed design.
